UNITED STATES PATENT OFFICE.

SALVATORE SCOGNAMILLO, OF NEW YORK, N. Y.

SPARK PLUG.

Application filed August 25, 1922. Serial No. 584,283.

To all whom it may concern:

Be it known that I, SALVATORE SCOGNAMILLO, a citizen of the United States, residing at New York city, in the county of New York and State of New York, have invented new and useful Improvements in Spark Plugs, of which the following is a specification.

This invention relates to sparking plugs, and the main objects of the same are, to provide a device of this character constructed to protect the electrodes from oil and hydro-carbon deposits, and to render the spark or its flash visible from the exterior of the plug to determine whether the plug is operating regularly and correctly. A further object of the invention is to generally improve the structures of sparking plugs and render the parts thereof convenient in assemblage as well as separation, and particularly to provide a removable electrode carrying plug. A still further object of the invention is to provide a sparking plug having a novel form of attaching means for the electric wires or connections and in some instances to preferably replace the ordinary form of binding post.

With these and other objects and advantages in view, the invention consists in the construction and arrangement of the several parts which will be more fully hereinafter described and claimed and which constitute improvements on the sparking plug disclosed by my Patent No. 1,200,243, dated October 13, 1916, and my pending application Serial No. 565,530, filed June 3, 1922.

In the drawing:

Fig. 1 is a side elevation of a spark plug embodying the features of the improvement; Fig. 2 is a transverse vertical section through the center of the plug as shown by Fig. 1;

Figs. 3, 4, 5, 6, 7, 8, 9, 10, 11 and 12 are detail views in section, elevation and plan, showing separated parts of the improved sparking plug;

Fig. 13 is a detail perspective view of the lower removable electrode plug;

Fig. 14 is a detail sectional view showing the manner of applying the electrical wire connection to the upper end of the plug by means of an ordinary binding or clamping screw;

Figs. 15 and 16 are, respectively, a side elevation broken away and top plan view of a preferred form of attaching clamp means

for the terminal of the electric wire connection;

Fig. 17 is a view similar to Fig. 2, showing a slight modification in the construction of the electrode plug and transparent enclosing hollow glass bell or casing;

Fig. 18 is a detail transverse sectional view of the hollow glass bell or casing; and

Fig. 19 is a transverse vertical section through an intermediate transparent plug used in both forms of the improved sparking plug.

The numeral 5 designates the plug body or shell, which is tubular or hollow and is formed with an upper chamber 6, as shown particularly by Fig. 9, the said chamber having a lower reduced portion 7 enclosed by a lower tubular extension 8 of the body or shell. Between the chamber 6 and the lower reduced portion 7 thereof an annular shoulder 9 is formed to serve as a support in a manner which will be presently explained. The inner side of the upper portion of the wall of the chamber 6 is screw-threaded, as at 10, this chamber opening through the upper end of the body or shell. The lower reduced portion 8 of the body or shell has inner screw threads 11 at the lower terminal thereof and a plurality of openings 12 above the screw threads, the openings being formed at regular intervals around this part of the body. As shown by Figs. 1 and 2, there are two rows of the openings 12, whereas in Figs. 9 and 17 a single row only of the openings 12 are provided. With the exception of the extra row of openings 12 as shown by Figs. 1 and 2, the body or shell 5 of both forms of the sparking plug are precisely similar, and the lower reduced portion 8 of the said shell or body has exterior screw threads 13 formed thereon. Within the chamber 6 a glass disk or block 14 is removably inserted and is held by the annular shoulder or seat 9. The disk or block has a central opening 15 extending vertically therethrough to receive an elongated metal sleeve or tube 16 preferably formed of brass and having near its lower end an annular shoulder 17 which rests on the top of the block 15, the lower end of the tube being externally screw-threaded as at 18 to receive a clamping nut 19 which bears against the lower side of the block or disk 14 and thereby holds the said tube 16 in upright fixed position. The upper extremity of the tube 16 is also formed with exterior

100

105

110

115

screw threads 20 for a purpose which will hereafter be explained. Extending through and immovably held in the tube 16 and depending below the nut 19 to within a short distance above the lower terminal of the lower reduced portion 8 of the body or shell 5 is an electrode rod or wire terminating at its upper end coincidently with the upper end of the tube and exposed through the latter. Applied over the tube 16 and bearing on the block or disk 14 is a transparent enclosure, which as shown by Fig. 2 is in the form of a cylinder 22 of equal diameter throughout its length. The disk or block 14 and the transparent enclosure 22 are held in place and in proper assembled relation to the body or shell 5 by a tubular nut 23 having a straight bore 24 of approximately the same diameter as the outer diameter of the transparent enclosure or cylinder 22, so as to snugly engage the latter and maintain the same in central position over and on the disk or block 14. The nut 23 has exterior screw threads 25 to engage the screw threads 10 at the upper part of the chamber 6, and is also provided with polygonal faces 26 for engagement by a wrench or other tool to facilitate application and removal of said nut. In the slightly modified form of the improved sparking plug as shown by Figs. 17 and 18, the transparent enclosure is in the form of a tapered bell 27 and the nut 28 has an inner correspondingly tapered bore 29 to snugly engage the outer side of the bell and hold the same in applied position. The upper reduced end 30 of the bell 27 has a bore 31 extending through the center thereof for the tube 16, and engaging a part of the threads 20 on the upper end 40 of the said tube is a nut 32 which is turned down against the upper reduced end 30 of the bell 27 to assist in securing the tube in place. In the structure shown by Figs. 1 and 2 a shouldered nut 33 is fitted in the upper end of the cylinder 22 and engages a portion of the threads 20 on the upper end of the tube 16. The nuts 32 and 33 are of course of metal and portions of the tubes in both forms of the improved device are permitted to project above the upper sides of the respective nuts 32 and 33 to receive a screw or binding cap 34, as shown by Fig. 14, to apply and make electrical contact with a terminal connection 35 of an electric wire or feeder 36. Between the lower end of the nuts 23 and 27 and each disk or block 14, and also between the latter and the shoulder or seat 9, insulating washers 37 and 38 are introduced to prevent breakage 55 of the disk or block 14, which as specified is of glass and more or less fragile. In the present form of the improved sparking plug the glass disk or block 14 is very simple in its construction, as shown in detail by Fig. 60

65 19.

In the lower screw-threaded end of the lower reduced portion 8 of the body or shell 5, as shown by Fig. 2, an electrode plug 39 is removably mounted, said plug as shown by Fig. 6 being provided with a lower screw-threaded flanged bottom 40 and an upwardly projecting socket or cup 41 fully open at its top and having electrodes 42 radially projecting thereinto. The lower screw-threaded flanged bottom 40 is imperforate 70 and has diametrically opposed recesses 43 for engagement by a spanner or analogous implement to facilitate application and removal of the said plug relatively to the lower end of the lower reduced portion 8 of the body or shell. In the slightly modified form shown by Fig. 17 the plug 44 has a series of openings 45 through the flanged bottom 46 thereof, but the open top cup or socket 47 is the same as that shown by Figs. 2 and 6 and also carries radially arranged electrodes 48 projecting thereinto. The lower extremity of the electrode rod or wire 21 projects downwardly through the open top of the cup or socket of each of the electrode plugs, as clearly shown by Figs. 2 and 3, and terminates above the bottom of the cup or socket between the inner ends of the electrodes projecting into the cup or socket, and by this means all of the electrode extremities are shielded from accumulation of deposits thereon or corrosion by oil thrown upwardly thereagainst. It will be understood that the modified form of the plug 44 is also readily removable and insertible 80 in the part of the shell to which it is adapted to be applied, and any suitable implement may be used for removing and setting the said latter plug. 90

It will be understood that the improved 100 sparking plug is adapted to be provided with any suitable form of binding post for attaching the terminal of the electric wire or connection 36 as shown by Fig. 14, and in some instances the user may desire the 110 cap or clamping nut 34, which is of simplified construction and fitted over the upwardly projecting end of the tube around the rod or wire 21. As a practical and quickly operable substitute for this usual or other analogous form of binding means for the terminal 35 of the electric wire 36, the clamp attachment shown by Figs. 15 and 16 may be used, said attachment comprising a lower 115 fixed jaw 49 projecting outwardly from and forming part of a cap nut 50 adapted to be applied over the upwardly projecting end of the tube enclosing a portion of the rod or wire 21. The outer end of the fixed jaw 49 is formed with an open slot 51, as shown by Fig. 16, between opposite apertured end ears or lugs 52 to pivotally receive corresponding ears 53 at the outer end of a movable jaw 54, the ears 52 and 53 being connected by a pivot pin or pintle 120 125 130

having a spring 56 surrounding the same and attached at one extremity to the jaw 49 adjacent to the pivotal connection and also to one of the ears 53, and whereby a spring 5 hinge connection is formed between the jaws 49 and 54. The inner end of the jaw 54 is free and has an upwardly projecting terminal 57 for engagement by the fingers of the operator to open or raise the jaw 10 against the resistance of the spring 56, the jaw when liberated closing with a snap and positively retained by the action of the spring against loose movement. The movable jaw 54 has an opening 58 therethrough 15 near the inner free end and the jaw 49 over the cap nut 50 is formed with a convex projection 59 to engage said opening 58. The terminal 60 of the electric wire 61 in this instance also has an opening 62 formed 20 therein to fit over the projection 57, the said projection extending upwardly far enough to enter the opening 58 when the jaw 54 is closed. It will be seen that by raising the movable jaw 54 against the resistance of the spring 55 the terminal 60 may be applied over the inner extremity of the fixed jaw 49 with the projection 57 extending through the opening 62 in the said terminal, and when the jaw 54 is released it will 25 snap down on the portion of the terminal thereunder and secure said terminal against accidental disengagement from this improved clamping attachment. The advantage of this attachment is that the wire terminal 60 may be readily and quickly attached to the sparking plug and also easily detached therefrom without requiring the manipulation of screw devices, and at the same time give the necessary positive contact between the engaging parts for transmission of the current. 30

The operation of the plug when applied to the cylinder of a motor or other explosive receiving chamber is very simple, and in the use of the plug with a cylinder of an internal combustion engine, the gas compressed by the piston of the cylinder is in part forced through the openings 12 above the plug 39, as shown by Figs. 1 and 2, or 35 through the single row of openings 12, and also through the openings 45 of the plug in the form of the device shown by Fig. 17, and is exposed to the electrodes within the cup or socket of the plug. The flash which ensues when the sparking action and ignition of the gas takes place will be exteriorly observable through the glass disk or block 44 and the transparent enclosure either in the form of the cylinder 22 or bell 27, particularly in view of the fact that the ignition is effected within the lower portion of the plug. The suction stroke of the piston will draw the exploded gas downwardly 40 from the plug and at the same time free the latter of hydrocarbon deposit, especially in

view of the fact that the electrodes are shielded against contact with the oil in the cylinder. In view of this shield of the electrodes the latter will remain clean and in positive working order for a materially 45 greater period than is possible in the ordinary form of sparking plug electrode arrangement. If, however, at any time it should be found necessary to remove and clean the electrodes, the sparking plug 39 or 50 44 may be detached and the electrodes easily reached for cleaning purposes, and subsequently the said plugs may be reapplied or reset. In view of the protection afforded the electrodes by the improved electrode plug, the necessity for removal of either form of plug for cleaning purposes will be required only at long intervals. 55

In addition to the advantages incident to the protection of the electrodes or sparking members of the improved plug, it will be seen that all the parts of the plug may be readily separated and reassembled. It is proposed to manufacture duplicate parts so that any one or more of the parts of the 60 plug may be replaced at a comparatively small cost when the remaining parts of the plug are in good working order, with material saving in the cost of sparking plug upkeep. In the application of the plug it will be understood that the same will be inserted in the cylinder of an internal combustion engine, or applied to any other explosive chamber through the medium of the exterior screw threads 13, the upper portion 65 of the body or shell being formed with the usual enlargement 63 for engagement therewith by a wrench or other tool adapted for applying and removing plugs. 70

It will also be understood that changes 75 in the proportions, dimensions and minor details of construction may be adopted without departing from the spirit of the invention. 80

What is claimed as new is: 85

1. In a spark plug, a body with an upper transparent closing means to render the flash of the electrodes exteriorly visible at the top of the plug to determine the character of operation of the electrodes, an electrode-carrying means removably applied to the lower end of the body and having a flat flanged bottom and an electrode holding cup rising from the upper side of said bottom with electrodes extending radially 90 thereinto, the cup being fully open at the top to expose the flash of the electrodes upwardly through the body, and an electrode device extending downwardly through the body and into the open top of the said cup, the cup being of less diameter than the interior of the said body and the latter adjacent to and around the cup being formed with openings. 95
2. A sparking plug body having openings 100

through the lower extremity thereof above the lower terminal edge of said body, an electrode plug removably applied to the lower end of the body and having a cup projecting from the upper side thereof and of less diameter than the interior of the adjacent portion of the plug body, the cup having an upper fully open top portion and provided with electrodes extending thereto, and an electrode device extending downwardly through the body and into the upper open top portion of the cup to cooperate with the electrodes of the latter.

3. In a spark plug having a body of non-transparent material, a transparent closing means at the upper portion of the body to render the flash of the electrodes exteriorly visible, the lower extremity of the body being provided with a series of openings above the lower terminal edge of said extremity, an electrode-carrying device removably fitted in and closing the lower end of the body and having an open top cup rising from the upper side thereof and of less diameter than the interior of the body, a conducting tube extending upwardly through the top portion of the body and partway downwardly through the said body, and an electrode device mounted in the tube and also extending into the said cup at its lower end.

4. A spark plug having a main body composed of non-transparent material, a transparent closing means associated with the upper portion of the body and serving to render the flash of the electrodes exteriorly visible, an intermediate horizontally disposed transparent disk fixed in the body, an electrode-carrying means removably applied to and closing the lower end of the body, the body having openings above its lower end and the electrode-carrying means provided with an upwardly extending cup with a fully open top of less diameter than the lower end of the body, the body between the transparent disk and the cup being tubular, and an electrode device extending downwardly through the center of the body and through the said disk and having its lower end projecting into the cup, the cup being provided with electrode devices to cooperate with the electrode device projecting into the cup.

5. A sparking plug having a body with a chamber in the lower portion thereof and openings therethrough adjacent to the lower end communicating with the said chamber, an electrode enclosing plug removably mounted in the lower end of the body and having an upwardly projecting cup within

the body, said cup being of less diameter than the interior of the body and having an open top portion and electrode devices extending thereto, the upper portion of the plug body being provided with transparent means for exteriorly disclosing the flash within the body, and an electrode device extending downwardly through the body and terminating within the cup to cooperate with the electrode devices of the latter.

6. A sparking plug having a body with a chamber in the lower portion thereof, an intermediately positioned horizontally arranged transparent disk within the body, the said disk having a central opening therethrough, a transparent closing means secured on the upper portion of the disk and forming a portion of the outer enclosure of the plug, a metal tube secured in the opening of the disk and extending through the top of the plug, an electrode plug removably mounted in the lower end of the body and having a cup device extending upwardly therefrom and open at the top, the cup device carrying electrodes therein, the body adjacent to the electrode plug having openings therethrough, and an electrode device extending downwardly through the tube and terminating in the cup device to cooperate with the electrodes of the latter.

7. A sparking plug having a body with a chamber therein, a transparent disk having a central opening therethrough and intermediately held within the body and dividing the chamber, a transparent closing means secured to the upper portion of the disk and exteriorly exposed at the top part of the plug, an electrode plug removably mounted in the lower end of the body and having openings therethrough and also provided with an upwardly projecting cup device with a fully open top, the cup device carrying electrodes, the lower extremity of the body being provided with openings adjacent to the plug and around the cup of the latter, a metal tube extending downwardly through the center of the upper portion of the plug and through the said disk, and an electrode device extending downwardly through the tube and terminating in the cup of the plug to cooperate with the electrodes of said cup.

In testimony whereof I have hereunto set my hand in presence of two subscribing witnesses.

SALVATORE SCOGNAMILLO.
